(57) **CLAIM**

The ornamental design for a trailer for proppant containers, as shown and described.

DESCRIPTION

[FIG. 1 is an upper perspective view of the trailer for proppant containers showing my new design.]

[FIG. 2 is a side elevation view thereof.]

[FIG. 3 is an opposite side elevation view thereof.]

[FIG. 4 is a front elevation view thereof.]

[FIG. 5 is a rear elevation view thereof.]

[FIG. 6 is a top plan view thereof; and.]

[FIG. 7 is a bottom plan view thereof.]

FIG. 8 is a top and front perspective view of a trailer for proppant containers showing my new design;

FIG. 9 is a side elevation view thereof;

FIG. 10 is an opposing side elevation view thereof;

FIG. 11 is a front elevation view thereof;

FIG. 12 is a rear elevation view thereof;

FIG. 13 is a top plan view thereof; and,

FIG. 14 is a bottom plan view thereof.

The [features presented in broken lines are for environmental purposes only and] *broken lines in the drawings illustrate portions of the trailer and environmental structures of two container bins that do not form no part of the claimed design.*
